MACHINE FOR MAKING PIPE BENDS

Joseph F. Staroba, Chicago, Ill., assignor to Taylor Forge & Pipe Works, Cicero, Ill., a corporation of Illinois

Application April 1, 1940, Serial No. 327,112

4 Claims. (Cl. 153—48)

This invention relates to the making of pipe fittings, such as elbows, U-bends and analogous articles.

It is known to produce pipe bends from straight tubular blanks by forcing the latter over an appropriately shaped enlarging mandrel. My invention is directed to a machine for making pipe bends in the manner stated, in which the mandrel is associated with a mandrel rod of a length to receive a plurality of blanks, means being provided for reciprocating the mandrel rod and for charging the latter with blanks when it is in its rearward position, at the end of a draw stroke, to the end of increased speed in operation and corresponding lowered cost of production. More specifically, I provide a reciprocating cross-head or equivalent member and quick detachable means for coupling such member to the rearward end of the mandrel rod, in conjunction with means for moving the latter rod into position with its rearward end clear of the cross-head and associated parts for reception of the blanks, means being provided for forcing the blanks forward along the mandrel rod in the loading position of the latter. Conveniently, the means for moving the rod into loading position is effective for raising the rearward end of the mandrel rod out of the coupling means and for lowering the rod, after loading or charging thereof with the blanks, into position with its rearward end disposed in the coupling member for coupling to the cross-head. I also provide means for restraining the mandrel rod against forward movement during loading thereof and, preferably, blank abutments of a character to facilitate the required movement of the rod for loading thereof with blanks. Further objects and advantages of my invention will appear from the detail description.

In the drawings:

Figure 1 is a central vertical lengthwise sectional view of a machine embodying my invention, certain parts being shown in elevation and certain other parts being broken away, the parts of the machine being shown in the positions which they occupy at the beginning of the draw stroke for forcing the blanks over the mandrel;

Figure 2 is a view similar to Figure 1 but showing the mandrel rod in the position it occupies at the end of the draw stroke and raised into loading position, with blanks being loaded onto the rod;

Figure 3 is a sectional view, on an enlarged scale, taken substantially on line 3—3 of Figure 1, the mandrel rod and the blanks thereon and

the furnace drawbar being omitted for clearness of illustration;

Figure 4 is a plan view, on an enlarged scale, of the rearward end portion of the mandrel rod 5 and the cross-head and associated coupling means, with the lock collar of the latter means in open or inoperative position, certain parts being broken away and shown in section;

Figure 5 is a sectional view taken substantially on line 5—5 of Figure 4; and

Figure 6 is a fragmentary lengthwise sectional view of the mandrel rod, showing in elevation the blank latch means.

In the embodiment of my invention illustrated by way of example the machine is provided with a main frame comprising suitable standards or uprights 6 and 7, these uprights supporting side I-beams 8. An annular cross member 9 is secured to the forward ends of beams 8, by welding or in any other suitable manner. Upper and lower blank abutment members or stops 10 and 11, respectively, are pivotally mounted on the front of cross member 9, for swinging movement in a vertical plane toward and away from the latter member. The members 10 and 11 are provided, in their adjoined edges, with arcuate openings which snugly receive a mandrel rod 12, when the stop members are in their normal position.

Member 10 is mounted by means of a pintle rod 10a secured to its upper portion. Rod 10a has a reduced element 10b adjacent each end, which elements operate in vertical slots 10c in lugs 10d secured to cross member 9. Member 10 is thus mounted for swinging movement and for vertical sliding movement and is urged into its normal position by gravity. Member 11 is pivotally mounted at its lower portion in substantially the same manner as member 10, but does not have vertical sliding movement. A weight 12, suitably attached to and depending from member 11, urges the latter into its normal position. Cross member 9 serves to restrain members 10 and 11 against rearward movement from their normal positions.

Mandrel rod 12 extends forwardly from the members 10 and 11 into a hood or furnace 13, of refractory construction. Suitable means, such as one or more gas burners 14, is provided for heating blanks on rod 12 and on a suitably formed enlarging mandrel 16 secured upon the forward end of rod 12, within furnace 13. The rod 12 is of a length to receive thereon a plurality of straight tubular blanks 17 disposed in endwise contacting relation, the rearward end of the rearmost blank on this rod contacting the blank

abutment members or stops 10 and 11 at the beginning of the draw stroke, for forcing the blanks over the mandrel, as shown in Figure 1. A grooved roller 18, supported by a bracket 19, suitably secured to the furnace structure, is disposed to support the mandrel rod and the blanks thereon.

In the operation of the machine, the mandrel rod 12 is reciprocated, being moved rearward during the draw stroke for forcing the blanks over the mandrel and, after being charged with a suitable number of blanks, returned to its forward position for a second draw stroke.

Within the broader aspects of my invention, any suitable means may be provided for reciprocating the mandrel rod. I have shown, for that purpose, a wheel mounted across head 20 traveling on rails 21 suitably secured to the inner faces of I-beams 8. Cross-head 20 is secured, in any suitable manner, to the forward end of a piston rod 22 which extends through a stuffing box 23 at the forward end of a hydraulic cylinder 24, the rearward end of rod 22 being suitably secured to a piston (not shown) mounted for reciprocation within cylinder 24. The latter is suitably secured at its forward end, as by bolting, to the I-beams 8 and may be supported in any suitable manner, as by means of a rearward extension of the main frame or, if desired, by separate supports. Suitable means is provided for admitting and exhausting liquid under pressure to the cylinder 24 at opposite sides of the piston for reciprocating the same, in a known manner. Such means is well known and need not be illustrated nor described here in greater detail. Suffice it to state that the rearward end of piston rod 22 is secured to a piston which is reciprocated in cylinder 24, and that suitable means is provided for supporting the latter cylinder and for controlling admission thereto of liquid under pressure from a suitable source of supply and exhaust of liquid from that cylinder, for the purpose stated. Any other suitable means may be provided for reciprocating the cross head or equivalent member, though I preferably employ the hydraulic means referred to.

The rearward end portion of mandrel rod 12 is formed to provide a reduced neck 26 of substantially V-shape in cross section, the forward end of this neck being connected to the body of rod 12 by a shoulder 27 inclined outward and forward of the rod. Neck 26 fits snugly into a corresponding socket 28 opening at the top and the forward end of a coupling member 29 secured at its rearward end, in a manner which will be described presently, to cross head 20 and extending forward therefrom. Coupling member 29 is provided, at opposite sides of socket 28, with spaced ribs 30 extending in direction from the top to the bottom of the socket. Ribs 30 receive between them correspondingly disposed ribs 31 formed on the sides of neck 26. In order to guard against casual displacement of neck 26 from coupling member 29, a lock collar 32 is mounted to turn upon the latter member, this collar being provided throughout its length with an opening or slot 33 of somewhat greater width than the top of socket 28. A suitable handle 34 is secured in collar 32 and projects substantially radially therefrom, for convenience in turning this collar into its operative or inoperative position. Turning movement of collar 32, in either direction, is limited by a stud 35 secured in coupling member 29, and projecting into a circumferential slot 36 in collar 32. In Figure 5, collar 32 is in its oper-

ative position, effective for closing the top of socket 28 and preventing displacement therefrom of neck 26 of the mandrel rod. When collar 32 is turned into its extreme position in the other direction, slot 33 thereof is disposed above the top of socket 28, and neck 26 may then be moved out of the coupling member 29, through slot 33 of collar 32, into position clear of the cross-head and the parts carried thereby, as will be explained more fully presently.

Cross-head 20 is secured on the forward end of piston rod 22 in any suitable known manner and is recessed from its forward end. Coupling member 29 is provided, at the rearward end of its body portion, with an element 38 of slightly increased diameter, this latter element being provided, at its rearward end, with an outwardly extending circumferential base flange 39 which fits snugly within the recessed body portion of cross-head 20. A securing nut 40 screws into the forward end of the cross-head and bears against the forward face of base flange 39, thus effectively clamping the coupling member 29 to the cross-head for movement therewith. Any other suitable means may be provided for securing the coupling member 29 to the cross-head or, if desired, the coupling member may be formed integrally with the cross-head, as will be understood.

Cross-head 20 is provided, at one side thereof, with a suitably disposed depending arm 41 having, at its lower end, an eye 42. The latter receives the threaded rearward end portion of a furnace drawbar 43 suitably attached, at its forward end, to furnace 13 as by being bent at right angles and inserted through a plate bracket 44 suitably secured to the furnace structure. Two nuts 45 and 46 are screwed upon drawbar 43 in contact with the front and the back, respectively, of eye 42. In that manner, furnace 13 is connected to the cross-head for movement therewith, for which purpose the furnace is suitably mounted on wheels 47 traveling upon rails, one of which is shown at 48, extending forwardly from the main frame of the machine in alignment therewith.

Ribs 31 of neck 26 of the mandrel rod 12 are spaced apart a distance somewhat greater than the width of ribs 30 of socket member 29, so that the neck 26 of the mandrel rod may be moved into and out of the socket member by swinging movement of this rod about a point adjacent the forward end thereof, as will be explained presently. In order to accomplish such swinging movement of the mandrel rod, I provide two hydraulic jacks 50, each provided at the upper end of its piston rod with a grooved roller 51. The rollers 51 are disposed in vertical alignment with piston rod 22, when the latter is in its forward position, and with mandrel rod 12 in the rearward position of the latter, the axes of rollers 51 being perpendicular to the common axis of piston rod 22 and mandrel rod 12. The jacks 50 are operated for raising and lowering the rollers 51 in a known manner which need not be illustrated or described here in greater detail. Suffice it to state that suitable means is provided for effecting vertical adjustment of the rollers 51 to desired extent. Normally the rollers 51 are in lowered position, as shown in Figure 1.

During the rearward or draw stroke of the mandrel rod 12, ribs 30 of the coupling member 29 are in contact with the forward faces of ribs 31 of neck 26 of the mandrel rod for moving the latter rod rearward with the cross-head 20 and

the piston rod 22. When mandrel rod 12 reaches its rearward position, at the end of the draw stroke, it is disposed above grooved rollers 51 and there may be a partially formed bend on the mandrel 16 and several blanks on the mandrel and the forward portion of rod 12, as shown in Figure 2. In order to load the mandrel rod with blanks, lock collar 32 is turned into its inoperative position, so as to uncover the top of socket 28 of coupling member 29. The rollers 51 are then elevated, the rearward one of these rollers being raised to a greater height than the forward one, thus swinging rod 12 on roller 18 upward into the upwardly and rearwardly inclined position shown in Figure 2, with the rearward end of this rod disposed above and clear of the cross-head and the parts carried thereby. In order to prevent forward movement of the mandrel rod, when thus supported, a holding pawl 53, pivoted upon the upper portion of cross member 9 at the rear thereof, is swung downward to position to engage into a notch 54 suitably located in the upper portion of rod 12, pawl 53 being then inclined downward and rearward in contact with the rearward end of the notch effective for preventing forward movement of the mandrel rod. To facilitate upward swinging of mandrel rod 12, the upper blank stop member 10 may be raised slightly, which is permitted by the slots 10c, and then swung forward into position with its lower edge resting upon the adjacent blank. Mandrel rod 12 is then swung upward and stop member 10 moves forward and upward into substantially its position shown in Figure 2.

When the mandrel rod 12 is supported in the position shown in Figure 2, blanks 17 may readily be placed upon this rod over the rearward end thereof by hand, the respective blanks being first inserted over neck 26, as indicated at 17a and then moved forward onto the body portion of the mandrel rod as indicated at 17b. From the position 17b the blanks are forced forward along mandrel rod 12, by suitable means. Preferably, I provide pusher means for that purpose. The pusher means may comprise a hydraulic cylinder 56 suitably mounted on the upper forward portion of the main cylinder 24, cylinder 56 receiving a reciprocating piston (not shown), to which is secured the rearward end of a piston rod 57 passing through a stuffing box 58 at the forward end of cylinder 56. A head 59 is secured upon the forward end of piston rod 57 and carries a depending pivotally mounted dog 60 capable of forward and upward swinging movement relative to head 59 but restrained, by a stop 61, against rearward movement relative to the head. Dog 60 is disposed to contact the upper rearward end portion of a blank in the position indicated at 17b on the rearward end portion of mandrel rod 12, so as to force the blank from the position 17b forward along rod 12 into the position of the next preceding blank on this rod, shown in full-lines in Figure 2. During this operation of forcing the blanks forward along the mandrel rod, from the position 17b, another blank may be placed over neck 26 of the mandrel rod, in the position 17a, and moved forward substantially into position 17b, it being noted that during the rearward movement of piston rod 57 and head 59 of the pusher dog 60 will swing upward and forward so as not to oppose such forward movement of the last referred to blank. When dog 60 has moved rearward sufficiently to clear the rearward end of the last referred to blank, piston rod 57 may be moved forward again, thus ad-

vancing this blank along the mandrel rod, upon which another blank may be placed in the manner described. It is thus possible quickly to load or charge the mandrel rod 12 with the proper number of blanks, while it is supported in the position shown in Figure 2, it being understood that the blanks cannot be advanced forward beyond the holding pawl 53 during this loading operation. Cylinder 56 has associated therewith suitable known means for admitting liquid under pressure, from a suitable source of supply, at either side of the piston and for exhausting liquid from the other side of the piston, in a known manner. Such means is known and need not be illustrated nor described here in greater detail. Suffice it to state that any suitable pusher means may be provided for feeding the blanks forward along the mandrel rod in the manner stated, though ordinarily I prefer to employ the hydraulic pusher means shown and described herein.

After the proper number of blanks have been loaded onto the mandrel rod in the manner stated, the jacks 5 are operated to lower this rod into horizontal position, lowering neck 26 into socket 28 of the coupling member 29, after which the rollers 52 continue their downward movement until returned to normal position. Lock collar 32 is then turned into its operative position shown in Figure 5, in which position it guards against casual displacement of the neck from the socket member. Holding pawl 53 is then released from the mandrel rod and may be turned upward and forward into its inoperative position shown in Figure 1. The blanks which have been charged onto the mandrel rod may then be moved forward along the latter, into position with the most forward of such blanks in contact with the rearward end of the rearmost blank remaining upon the rod from the previous draw stroke, all of the blanks being disposed in endwise contact one with the other. During such forward movement of the blanks, the abutment members 10 and 11 are displaced thereby and, when the last blank has been advanced into position in front of the abutment members, are automatically returned to operative position about the mandrel rod. The cross head 20 is then moved forward, thus moving the rod 12 forward sufficiently to dispose the rearward end of the rearmost blank on this rod in front of the blank stop or abutment members 10 and 11 and to permit movement of such members to position fitting about mandrel rod 12. During this forward movement of the cross head the furnace 13 also is moved forward and the ribs 30 of coupling member 29 are in contact with the rearward faces of ribs 31 of neck 26. The cross head is then moved rearward a short distance, bringing the rearward end of the rearmost blank upon rod 12 into contact with the blank abutment members 10 and 11, at which time the parts occupy the positions shown in Figure 1, after which the continued rearward movement of the cross head and of the mandrel rod with it constitutes the draw stroke for forcing the blanks over the mandrel in the manner previously described.

Alternatively, after the proper number of blanks have been loaded onto rod 12, the latter may be coupled to the cross-head and moved thereby forward sufficiently to dispose the rearmost blank in front of the blank abutment members 10 and 11. During such forward movement of the mandrel rod the latter may tend to move through the blanks which have been loaded thereon, due

to contact of the forwardmost one of such blanks with stop members 10 and 11, which return to their normal position upon lowering of rod 12 into horizontal position. A latch member 65 is pivoted at one end, at 66, in an appropriately formed slot 67 in mandrel rod 12, adjacent the inner or rearward end thereof. Latch member 65 normally is held raised by a leaf spring 68, and is so disposed that a finger 69 thereof projects beyond mandrel rod 12 in position to contact the rearward end of the last blank loaded onto the rod. The forward edge of finger 69 is substantially straight and radial to rod 12, and the rearward edge of this finger is inclined outward and forward of the mandrel rod, as shown. The blanks being loaded upon the mandrel rod will readily pass over finger 69, depressing the latch member, and forward travel of the blanks with mandrel rod 12 is assured by the latch member, as will be obvious.

After the mandrel rod has been moved forward sufficiently to dispose the rearmost blank in front of the stop members 10 and 11, the latter are automatically returned to operative position about rod 12, in back of the rearmost blank. The cross-head is then moved rearward, drawing rod 12 through the blanks loaded thereon until all of the blanks on the rod are in endwise contact. Thereafter the cross-head continues its rearward travel, moving mandrel rod 12 rearward on its draw stroke.

I claim:

1. In a machine for making pipe bends, a frame, a fixed cross-member on said frame, a mandrel rod for receiving tubular blanks passing through said member, the latter having an opening of materially greater diameter than said rod, blank abutment means at the front of said member restrained thereby against rearward movement and yieldingly held in position extending about said rod, a mandrel at the forward end of said rod, a reciprocating cross-head mounted on said frame in rear of said member, a coupling member carried by said cross-head provided with a socket opening through its top and forward end, the rearward end of said rod being insertible into and removable from said socket by lowering and raising thereof, said coupling member and the rearward end of said rod having cooperating means securing them together when coupled, means normally restraining the rearward end of said rod against movement out of said socket adjustable to permit such movement, means disposed beneath said rod in its rearward position for raising its rearward end clear of said socket member and there supporting it and for lowering the rearward end of said rod into said socket, and means for forcing blanks placed over the rearward end of said rod when in its raised position forward along said rod.

2. In a machine for making pipe bends, a frame, a fixed cross-member on said frame, a mandrel rod for receiving tubular blanks passing through said member and having a mandrel at its forward end, blank abutment means at the front of said member restrained thereby against rearward movement and yieldingly held in position about said rod, a reciprocating cross-head on said frame in rear of said member, means for coupling said rod to said cross-head comprising a coupling member carried by said cross-head and having a socket opening through its top and forward end, the rearward end of said rod being insertible into and removable from said socket by lowering and raising of said rod, and a slotted lock collar turnable on said coupling member into a first position closing the top of said socket against upward movement therethrough of the rearward end of said rod and a second position opening the top of said socket for relative upward movement of said rearward end of said rod.

3. In a machine for making pipe bends, a mandrel rod and a mandrel at the forward end thereof, means for reciprocating said rod comprising a fixed cylinder and a piston rod reciprocating therein, means for coupling the rearward end of said mandrel rod to the forward end of said piston rod, removable blank abutment means disposed about said mandrel rod restrained against rearward movement, pusher means at the forward end of said cylinder above said mandrel rod and operable independently of said reciprocating means, the rearward stroke of said mandrel rod being its draw stroke and serving to position it with its rearward end substantially beneath said pusher means, and means for raising said mandrel rod when it is uncoupled from said piston rod and supporting it with its rearward end in position spaced from said reciprocating means for reception of blanks and for movement forwardly therealong of the blanks by said pusher means.

4. In a machine for making pipe bends, a mandrel rod and a mandrel at the forward end thereof, means for reciprocating said rod comprising coupling means at the rearward end thereof, removable blank abutment means disposed about said rod restrained against rearward movement, pusher means operable independently of said reciprocating means, the rearward stroke of said rod being its draw stroke and serving to position it with its rearward end adjacent said pusher means, and means for supporting said rod when uncoupled from said reciprocating means in its rearward position with its rearward end spaced from said reciprocating means and in proximity to said pusher means for receiving blanks and for movement forwardly therealong of the blanks by said pusher means.

JOSEPH F. STAROBA.

CERTIFICATE OF CORRECTION.

Patent No. 2,288,753.

July 7, 1942.

JOSEPH F. STAROBA.

It is hereby certified that error appears in the printed specification of the above numbered patent requiring correction as follows: Page 4, second column, lines 43 and 44, claim 4, for "a drel rod" read --a mandrel rod--; and that the said Letters Patent should be read with this correction therein that the same may conform to the record of the case in the Patent Office.

Signed and sealed this 18th day of August, A. D. 1942.

Henry Van Arsdale,

(Seal)

Acting Commissioner of Patents.
